MESSAGE DELIVERY DEVICE

William R. Hall, Kingsville, Ontario, Canada

Application November 16, 1940, Serial No. 365,881

4 Claims. (Cl. 258—2)

This invention relates to improvements in train order or message delivery hoops and a support therefor.

At the present time when it is desired to deliver a train order to the engineer of a passing train the station agent attaches the message to a delivery cord loop and strings the cord releasably upon a delivery hoop. The agent then holds the hoop up toward the passing train in such a position that the engineer can pick off the cord with its attached message. The delivery of a message in this manner requires the agent to stand dangerously close to the moving train and if the train is a double header and it is desired to deliver a message to the driver of each engine two hoops, each equipped with a cord, are required and the difficulties of the agent's task are substantially increased.

One object of this invention is to provide a simple form of holder or support for a message delivery hoop. This support is so constructed that the delivery hoop when mounted thereon is positioned in such a manner that the cord carrying message may be readily picked off the hoop by the engineer of a passing train. My improved holder is of such a character that the delivery hoop may be readily mounted thereon, is securely held thereby and may be easily removed after use.

Another object is to provide a train order delivery hoop which is so constructed that two separate messages or train orders may be delivered in succession therefrom to two different recipients. For example, my improved hoop is of such a character that it may be equipped with two delivery cords each carrying a message. One cord carrying its message is supported upon the hoop to be picked off by the engineer of the first engine of a double-header passing train while the second cord carrying its message is supported upon the hoop to be picked off by the engineer of the second engine of the double header. During the picking off of the first message cord the second message cord is supported in a retracted position so as not to be disturbed. The operation of picking off the first message cord releases the supporting mechanism of the second message cord and causes it to be thrown into position to project the second message cord into position to be grasped. These two message cords are picked off in succession. Only one message cord is in position at one time to be picked off.

This improved device is simple, inexpensive and of sturdy construction. It comprises a mini-

mum number of parts. It is easy to load and operate. The second delivery cord is so supported that during delivery of the first message cord the second cord is positioned in such a manner that it will not be accidentally engaged or released by the engineer in picking up the first message cord.

Other objects, advantages, and meritorious features of my invention will more fully appear from the following description, appended claims, and accompanying drawing, wherein:

Figure 1 is an elevation of a signal post partly broken away provided with my improved hoop holder and improved hoop structure with the hoop arranged to deliver two messages and with the first message cord supported for delivery and the second message cord held in the retracted position,

Fig. 2 is an elevation of a fragment of my improved hoop enlarged over the view of Fig. 1 and arranged as shown in Fig. 1,

Fig. 3 is a plan of a fragment of the structure shown in Fig. 1 taken on line 3—3,

Fig. 4 is an elevation of my improved hoop showing the second message cord projected for delivery, and

Fig. 5 is a cross section taken on line 5—5 of Fig. 1.

In Fig. 1, 10 indicates a signal post such as is provided alongside the railway track in front of railway stations. I propose to utilize this upright post as a support of my improved hoop holder. The hoop holder itself comprises a bracket arm 12 and a brace 14 which is pivoted to the arm as at 16. The arm is provided at one end with a clamp 18 in the form of a loop which is adapted to be bolted about the post 10. There is bolted about the post below the loop 18 a second clamp or loop 20 and the free end of the brace is seated within spaced portions 22 of this clamp 20 so as to hold the bracket arm in the upright position shown in Fig. 1.

This bracket arm is provided on one side as at its outer end with a hook 24 and with a pin or bolt 26 spaced inwardly toward the post from the hook. The hook opens upwardly and is of a size to receive the handle 28 of the message delivery hoop and this handle is provided with a pin aperture 30 indicated in dotted outline in Fig. 3 adapted to receive the pin 26 as shown in such figure to secure the hoop to the bracket. In this position the hoop handle is adapted to rest in the hook to project the hoop outwardly as shown in Fig. 1. The hoop may be quickly placed in position by inserting the pin through

the aperture and drawing the handle into the hook and may be as readily withdrawn. Upon removal of the brace bar 14 from its support in clamp 20 the entire holder may be dropped downwardly alongside of the post 10.

In the structure illustrated I have shown an improved type of double hoop. It is apparent that a single hoop such as is now used might have its handle provided with a pin aperture and might be supported upon the bracket arm as shown.

My improved hoop structure comprises a hoop which is generally Y-shaped. There is a handle 28 one end of which is provided with a pin aperture 30 as hereinafter described. At the opposite end there is a pair of arms 32 which form a fork adapted to carry a message delivery cord 34. In Fig. 1 a message 36 is shown attached to the cord. The cord is strung over the outer ends of the arms which are notched to hold it and extends rearwardly to be received underneath a spring catch 38 as shown in the figures of the drawing.

There is a second fork structure having arms 40 and which second fork is similar to the fork heretofore described but is of smaller size to be received within the first fork and substantially within its plane as shown in Fig. 4. This second fork is hinged at its base as by hinge 42 to the base of the first fork. The hinge is a spring hinge, the spring being indicated at 46, and the spring operates to normally hold the second fork substantially within the plane of the first fork. This is a conventional spring hinge structure. A pair of rubber bumpers 48 are provided to position the second fork when it is drawn into the first fork as shown in Fig. 4.

The second fork is adapted to be equipped with a message delivery cord 50. This cord is also adapted to carry a message. The second fork is provided at its base with a spring catch 52 similar in construction to the spring catch 38 and adapted to receive thereunderneath the cord 50 to hold the same strung upon the fork in the same manner as has been described with respect to the cord of the first fork.

This second fork is adapted to occupy either a position within the plane of the first fork as shown in Fig. 4 or a position swung out of said plane and substantially normal thereto as shown in Figs. 1, 2 and 3. In order to maintain the hinged fork in the last named position the fork is provided with a tripping lever 54 pivoted thereto at 56 rearwardly of the spring catch 52. This lever is provided with a notch 58 adapted to engage a part 60 on the first fork to hold the second fork at the position shown in Figs. 1 to 3 against the tension of its hinge spring. It will be noted that in this position the tripping lever overhangs the cord 34 which is strung upon the first fork. When this cord is picked off its hoop and as it is withdrawn therefrom it trips the lever 54 releasing the second fork to the urging of its spring hinge which throws the second fork into the position shown in Fig. 4 for delivery of its message.

In operation, therefore, the hoop is disposed as shown in Fig. 1. The second fork is retracted at one side so as to be entirely out of the way. The driver of the first engine picks off the cord 34 from the first fork with its attached message and this operation releases the second fork to the action of its spring and the second fork is thrown into the position shown in Fig. 4 so that

the driver of the second engine may pick off the cord 50. During the operation of picking off the first cord the second cord is held out of the way so as not to be disturbed.

5. What I claim:

1. A train message delivery hoop comprising, in combination, a Y-shaped hoop provided with a spring catch at the base of the two arms of the Y, a cord loop releasably engaged by said catch and extending along the two arms of the Y and across the open end between the open arms, a second pair of connected arms provided with a spring catch at the base of the arms, a cord loop releasably engaged by said catch and extending along the two arms and across the open end between the arms, said second pair of arms hinged to the first pair of arms and adapted to occupy a position alongside of the first pair of arms substantially in parallelism therewith or to be swung to a position substantially normal to the first pair of arms, spring means connecting the two pairs of arms urging said second pair of arms to occupy the first named position, means releasably connecting the two pairs of arms adapted to releasably hold said second pair of arms at said last named position counter the urging of said spring, said means having a part releasably engaged by the cord on the first pair of arms to be actuated thereby to release the second pair of arms to its spring means upon withdrawal of the cord from the first pair of arms.

2. A train message delivery hoop comprising, in combination, a cord carrying fork having a handle at its closed end, a spring catch on the base of said fork, a second cord carrying fork hinged to the first fork to be swung to lie substantially within the plane of the first fork or to be swung out of said plane, a spring catch on the base of the second fork, a cord loop releasably mounted upon each fork extending across the open end thereof and detachably engaged by the spring catch at the base of each fork, spring means connecting the two forks normally urging the second fork to a position substantially within the plane of the first fork, a tripping device adapted to releasably connect the two forks to hold the second fork against the tension of its spring and out of the plane of the first fork, said tripping device having a part overhanging the cord on the first fork to be actuated thereby upon withdrawal of the cord from the first fork to release the second fork to the urging of its spring.

3. A train message delivery hoop comprising, in combination, a cord carrying fork having a handle at its closed end, a spring catch on the base of said fork, a second cord carrying fork of a size to be received within the first fork and hinged to the first fork to be swung to a position to lie substantially within the plane of the first fork or to be swung to a position at a right angle thereto, a spring catch on the base of the second fork, a cord loop releasably mounted upon each fork and detachably engaged by the spring catch on the base of each fork, spring means connecting the two forks and normally urging the second fork to a position within the plane of the first fork, a tripping lever hinged to the base of the second fork rearwardly of the spring catch on the fork, lever engaging means on the base of the first fork disposed forwardly of the spring catch on the fork and adapted to engage the tripping lever to hold the second fork out of the plane of the first fork against the tension of the spring means acting upon the second fork.

4. A train message delivery device comprising, in combination, a cord carrying fork having a cord catch at its closed end, a second cord carrying fork having a cord catch at its closed end, said second fork being hingedly supported within the first fork for swinging movement from a position substantially within the plane of the first fork to a position substantially normal to the plane of the first fork, a message delivery cord releasably strung on each fork, each cord releasably engaged by the cord catch on the fork and extending along the two arms of the fork and across the open end between the two arms, a spring connecting the two forks urging the second fork to

5 its position within the plane of the first fork, a tripping lever mounted on the base of one fork, a lever engaging part mounted on the base of the other fork, said lever adapted to releasably engage said part to releasably hold the second fork at its position substantially normal relative to the first fork counter the urging of said spring, said cord strung on the first fork being engaged with the lever and adapted upon withdrawal of the cord from the first fork to trip the lever to release the second fork to the urging of the spring.

10 WILLIAM R. HALL.
